MULTISTAGE FREQUENCY REDUCER

Kurt Schlesinger, Berlin, Germany, assignor, by
mesne assignments, to Loewe Radio, Inc., a cor-
poration of New York

Application July 6, 1937, Serial No. 152,001
In Germany July 8, 1936

1 Claim. (Cl. 250—36)

Multistage frequency reducers are required in the construction of electrical synchronisation generators for television. In my application Ser. No. 92,153 of July 23, 1936, there is set forth 5 an apparatus of this nature, in which the frequency reduction is performed with pentodes which oscillate at the lower frequency and the intercepting grid of which is excited by the higher synchronising frequency.

10 The difficulty arises that the frequency reducers perform synchronisation only when the synchronising potential has a certain definite amplitude value. This value depends on the characteristic of the controlled stage insofar as 15 in the case of a smaller value the synchronisation will not work at all, whilst in the case of an over-excitation the oscillations generated in the controlled stage is disturbed and altered in frequency.

20 It is necessary, therefore, to provide a coupling between the two stages of the frequency reducers which fulfills two conditions:

1. In the case of zero coupling both circuits, the synchronising circuit and the controlled one, 25 must oscillate at their natural frequencies without influencing each other, so that it is possible to tune them approximately to the proper ratio before coupling them.

2. It must be possible, to increase the coupling 30 from zero continuously up to the value at which the synchronisation takes place without altering the natural frequency of either oscillator.

The invention is more clearly explained in the accompanying drawing in which

35 Fig. 1 shows a diagram of the circuit connection of two frequency reducer stages according to the present invention, whilst

Fig. 2 shows a modification of this diagram.

In Fig. 1 there is shown a connection of this kind which has been found to be very suitable in practice. The controlled oscillator is a pentode 1, having a control grid 7, a screening grid 8 and an intercepting grid 9. It oscillates with the frequency of its grid circuit. In order that 40 this frequency will depend as little as possible on the mains potential the generator 1 produces its grid bias itself by means of a cathode resistance 4 shunted by a condenser 5. In order that the amplitude of the oscillation is limited and that 45 its frequency depends as little as possible on the individual properties of the tube there are provided a grid-current limiting resistance 6 and an anode-current limiting resistance 18. The potentiometer 19, 20 of the screening grid is not 50 connected to the cathode 4, but directly to earth,

so that the anode current of the tube 1 is to a large extent independent of fluctuations in the mains potential. The resistance 20 is, for avoiding humming, shunted by a condenser 21.

The synchronising potential is conducted to 5 the intercepting grid 9. Since the currents taken up by the intercepting grid have considerable influence on the frequency, there is connected a limiting resistance 10 in series to it. Its bias is, via a resistance 11, equal to that of the cathode.

The synchronising potential is derived from the anode circuit of the preceding stage 2. In series with the reaction coil 12b of this stage, which oscillates at an n times higher frequency, 15 is a potentiometer 14'. Its slider is connected by a coupling condenser 15' to the intercepting grid circuit 10, 11 of tube 1. By moving the slider the coupling between both oscillators can be varied from zero to a sufficient degree.

For fine adjustment of the frequency of the circuits 12a, 3 (and 12a', 3') there is employed a small resistance 16 (resp. 16') in series with the inductance. The direct current is kept off at least from coil 12b having an iron core by means 25 of a coupling condenser 17.

If all coils 12b are blocked by condensers, they may according to Fig. 2 be connected in series with the potentiometers 14, instead to the positive pole of the mains, to the cathode of the 30 next stage. This connection avoids that ripples and humming noises or traces of oscillations are transmitted from the anode of one stage to the next one.

I claim:

A frequency changing apparatus comprising a first thermionic tube having an anode, a cathode and a grid electrode, an oscillation circuit comprising serially connected inductance and variable resistance elements and a capacity 40 shunted across said serially connected elements, said oscillation circuit being connected between said grid electrode and the cathode of said tube, an inductive member connected in the anode-cathode circuit of said tube and coupled to the 45 inductance element of the said oscillation circuit, potentiometer means connected in series in said anode-cathode circuit, an impedance member, resistive means connected serially with said impedance member and a portion of said potentiometer resistance, a second thermionic tube having an anode, a cathode, a plurality of grid electrodes, means for impressing signals developed across the last named resistance means 50 between one grid electrode and the cathode of 55

said second thermionic tube, a second oscillation circuit comprising inductance means and variable resistance means connected serially one with the other, a capacity means shunted across said serially connected resistance means and inductive means, said oscillation circuit being connected between another grid electrode and the cathode of said second thermionic tube, and inductive

means connected in the anode-cathode circuit of said second thermionic tube and coupled to the inductive means contained in said second oscillation circuit, said first oscillation circuit and said second oscillation circuit being tuned to harmonically related frequencies. 5
